LADY'S COAT WITH DETACHABLE HOOD

Samuel Saparow, Los Angeles, Calif.

Application May 22, 1950, Serial No. 10,080

Term of patent 3½ years

(Cl. D3—4)

To all whom it may concern:

Be it known that I, Samuel Saparow, a citizen of the United States of America, residing at Los Angeles, in the county of Los Angeles, State of California, have invented a new, original, and ornamental Design for a Lady's Coat with Detachable Hood, of which the following is a specification, reference being had to the accompanying drawing, forming a part hereof.

Fig. 1 is a front elevational view of a lady's coat with detachable hood, showing my new design.

Fig. 2 is a side elevational view of the lady's coat with detachable hood; and

Fig. 3 is a rear elevational view of a lady's coat with detachable hood embodying my new design.

I claim:

The ornamental design for a lady's coat with detachable hood, as shown.

SAMUEL SAPAROW.
